UNITED STATES PATENT OFFICE

Serial No. 531,350, filed April 17, 1944, and assigned to James B. Reeves, Whitefish Bay, Wis., assignor to Cutler-Hammer, Inc., Milwaukee, Wis., a corporation of Delaware.

Filed as nonprosecuted case 100,000,000 on April 17, 1944, and abandoned on June 1, 1945.

ELECTRONIC ENERGY CONVERSION AND CONTROL SYSTEM

Application April 17, 1944, Serial No. 531,350
(Cl. 172—239)

8. Claims.

The invention relates to the control by electronic means for motors and other translating circuits.

The control comprising this invention has certain features in common with that of my copending application, Serial No. 531,090, filed April 14, 1944, and assigned to the same assignee as the present application and is particularly advantageous for similar uses but is not limited thereto.

An object of the invention is to provide an improved electronic system for the control of rectified energy derived from an alternating current source.

Another object is to provide a control system of the aforementioned character wherein a gaseous tube is rendered conducting in accordance with control variations in the amplitude of a saw-tooth voltage impressed upon a control grid of said tube.

Another object is to provide a system of the aforementioned type employing a plurality of tubes for supplying energy from an alternating current source in rotation by applying to the control element of each tube a saw-tooth voltage of a substantially fixed wave shape and varying the instantaneous potential of said saw-tooth voltage with respect to the main electrodes of the respective controlled tube.

Another object is to provide in a control system of the aforementioned type a separate oscillator for each control tube and impress the voltage of said oscillator upon a control element of said tube.

Other objects and advantages will hereinafter appear.

In the drawings:

Figure 1 is a diagram of a system embodying the invention.

Fig. 2 is a diagram to illustrate the functioning of the control of certain gaseous discharge tubes forming part of the system, while

Fig. 3 is a modification of a part of the system shown in Fig. 1.

Fig. 4 is a diagram to illustrate the functioning of the modification shown in Fig. 3.

Referring to Fig. 1, the system comprises a transformer 1, having a primary winding 1^a connectable to a source of alternating current supply, and a center tapped secondary winding 1^b, provided with a number of additional taps as will be explained hereinafter.

The transformer supplies energy to the armature 2^a of a motor 2, which is also provided with a field winding 2^b. The winding 1^b has a center tap 1^c, end taps 1^d and 1^e, intermediate taps 1^f

and 1^g, located between the taps 1^d and 1^e, and intermediate taps 1^h and 1ⁱ located between the taps 1^e and 1^c. The tap 1^d is connected to the anode 3^a of a gaseous discharge tube 3, which is also provided with a cathode 3^b and a grid 3^c. The tap 1^e is connected to the anode 4^a of a gaseous discharge tube 4, which has a cathode 4^b and a control grid 4^c. The two cathodes 3^b and 4^b are connected through the primary winding

5^a of a transformer 5 to one terminal of the armature 2^a. The center tap 1^c of transformer 1 is connected to the second terminal of the armature 2^a. The transformer 5 has a secondary winding 5^b which is connected in a loop with the half-wave rectifier 6, the variable resistor 7, the condenser 8 and the half-wave rectifier 9. The two rectifiers 6 and 9 are so connected that current in said loop can flow only in one direction. A variable resistor 10 having a movable contact 10^a is connected between the common point of the cathodes 3^b and 4^b and the center tap 1^c of the transformer 1. The movable contact 10^a is connected to the common point of the condenser 8 and the rectifier 9. To control the currents of the tubes 3 and 4 the system is further provided with a transformer 11, having a primary winding 11^a which is connected across the taps 1^e and 1ⁱ of transformer 1. A resistor 12 and a condenser 13 are connected in series with each other to form a phase-shifting circuit in parallel with the primary winding 11^a. A third transformer 14 has a primary winding 14^a and a secondary winding 14^b. One terminal of winding 14^a is connected to the common point of the resistor 12 and the condenser 13, while the other terminal of said winding is connected to the center tap 1^c. The transformer 11 also has a center tapped secondary winding 11^b. The end terminals 11^d and 11^e of said secondary winding 11^b are connected to the anodes 15^a and 15^b, respectively, of a full-wave rectifier 15, which is also provided with a cathode 15^c.

The secondary winding 14^b has a center tap 14^c which is connected to the center tap 11^e of the winding 11^b and also to one terminal of a condenser 16, the other terminal of which is connected to the cathode 15^c. The end terminals 14^d and 14^e of the winding 14^b are respectively connected through the resistors 17 and 18 to the grids 19^a and 20^a of gaseous electron tubes 19 and 20, respectively. The tubes 19 and 20 are further provided with cathodes 19^b and 20^b, respectively, and anodes 19^c and 20^c, respectively. The cathodes 19^b and 20^b are jointly connected to one terminal of a condenser 21, the second ter-

55

inal of which is connected to the center tap 14^c of transformer 14 . A variable resistor 22 has one of its end terminals connected to the center tap 14^c , while its other end terminal is connected in series with an inductance 23 to the cathode 15^c . Connected in parallel with the resistor 22 is a condenser 24 . The variable resistor 22 is provided with a sliding contact 22^a which is connected to the common point of the resistor 7 and the condenser 8 . The resistor 22 is further provided with an intermediate tap 22^b which is connected to the cathodes 19^a and 20^a . Connected between the center tap 14^c and the anode 20^b , is a condenser 25 , and a similar condenser 26 is connected between the center tap 14^c and the anode 19^b . A resistor 27 has one terminal connected to the anode 19^b and a similar resistor 28 has one terminal connected to the anode 20^b . The two other ends of the resistors 27 and 28 are jointly connected to the common point of the resistor 22 and the condenser 24 . The anode 20^b is further connected through a resistor 29 , to the grid 4^c , while the anode 19^b is connected through a resistor 30 to the grid 3^c .

The field winding 2^b of the motor is supplied with energy through a pair of gaseous electron tubes 31 and 32 , having cathodes 31^a and 32^a , respectively, anodes 31^b and 32^b , respectively, and grids 31^c and 32^c , respectively. The anode 31^b is connected to the intermediate tap 1^b , while the anode 32^b is connected to the intermediate tap 1^c . The cathodes 31^a and 32^a are jointly connected to one terminal of the field winding 2^b , while the other terminal of said winding is connected to the center tap 1^c .

A transformer 33 is provided with a primary winding 33^a , which receives energy from the same source as the winding 1^a . The transformer 33 has also a center tapped secondary winding 33^b , the center tap being connected to the grid 31^c , while a center tapped resistor 34 is connected between the grid 31^c and the grid 32^c . The center tap of said resistor is connected to the common terminal of the cathodes 31^a and 32^a . One of the end terminals of the winding 33^b is connected to one terminal of a condenser 35 , the other terminal of said condenser being connected to the grid 32^c . A variable resistor 36 is connected between the second end terminal of the winding 33^b , and the grid 32^c . Said resistor 36 is provided with a tap 36^a and is also provided with a sliding contact 36^b by means of which the value of part of the resistor nearest to the grid 32^c may be varied.

Connected in parallel with the motor armature 2^a is the winding 37^a of a voltage responsive relay 37 , which relay has normally closed contacts 37^b connected between the intermediate tap 36^a of the resistor 36 and the grid 32^c .

The system shown in Fig. 1 operates as follows: Be it assumed that the primary windings of the transformers 1 and 33 are connected to an alternating current source of supply, thereupon a voltage is then induced in the secondary winding 1^b of transformer 1 , and in turn a voltage is impressed upon the primary winding 11^a of the transformer 11 . This induces a secondary voltage in the winding 11^b which impresses alternating voltages displaced by 180 degrees from each other between the cathode 15^c of the tube 15 and the anodes 15^a and 15^b , respectively. These voltages appear as a rectified voltage between 15^c and the tap 14^c of transformer 14 which is smoothed out in the usual manner by the condensers 16 and 24 and the inductance 23 ,

and a direct current flows through the resistor 22 .

The direct current voltage impressed upon the resistor 22 tends to charge the condenser 25 , the current flowing from the positive terminal of resistor 22 , through the resistor 28 , condenser 25 and back to the negative terminal of resistor 22 . A similar charging current will flow through the resistor 27 to the condenser 26 , so that the two condensers 25 and 26 are charged.

10 The transformer 14 is also energized so that the terminals 14^d and 14^e become alternately positive with respect to the center tap 14^c . Assuming that the terminal 14^d is positive with respect to the center tap 14^c , then the grid 20^c of the tube 20 is positive with respect to the cathode 20^a , to render the tube 20 conducting, thereby substantially short circuiting the condenser 25 so that it cannot be charged. However, during the same half cycle the grid 19^c is negative with respect to the cathode 19^a , so that the condenser 26 is being charged. The rates of charge of the condensers 25 and 26 are determined by the value of the resistors 28 and 27 , respectively, and also by the positive grid bias resulting from the voltage difference between the lower end of the resistor 22 and the tap 22^b . As the charge of the condenser 26 increases, the anode 19^b becomes increasingly negative with respect to its cathode 19^a . This also increases the negative potential of the grid 3^c , with respect to the cathode 3^b and the tube 3 is rendered nonconducting. The potential of the grid 3^c with respect to the cathode 3^b is further modified by the voltage drop in the upper partition of the resistor 10 , which affords an adjustable positive biasing component. The condenser 25 and tube 20 function in a manner similar to that described to affect the grid 4^c . The potential of the grids 3^c and 4^c may be further modified by any voltage which is induced in the winding 5^b as modified by the voltage drop through the resistor 7 , and by the potential of the sliding contact 22^a with respect to that of the cathode 15^c , as will be more fully explained hereinafter.

45 The armature 2^a is supplied with alternate half waves of rectified current from the transformer winding 1^b , through the tubes 3 and 4 . By varying the moment during the respective potential half cycle at which the tubes 3 and 4 become conducting, the effective current supplied to the motor armature 2^a may be varied.

50 The way of changing the moment of starting the conduction of current through these tubes will now be explained. Referring to Fig. 2 the curve A is the voltage which is available between the cathode and anode of the tube 3 during a given half cycle of said voltage. This is substantially the voltage between the center tap 1^c and the end tap 1^d . The tube 3 will be rendered conducting if the grid potential is at least as high as, or more positive than, the ignition potential indicated by the curve B. To attain this ignition grid potential at any given moment, the system is arranged to charge the condenser 26 to a gradually increasing potential indicated by the line C, and to discharge the condenser again substantially instantaneously approximately at the end of said half cycle represented by curve A, as indicated by the curve D. It will be obvious that when the potential C of the condenser equals the value B, the tube begins to conduct and it continues to conduct in a well known manner substantially to the end of the half cycle. To vary the point at which the line C intersects the curve B, a positive direct current potential bias E is added to the potential C resulting

in a grid potential represented by line C' and thereby shifting the moment during the half cycle when the grid potential equals the ignition potential B.

During the next half cycle of the available voltage the tube 4 is rendered conducting and the moment when it starts conducting is controlled in a manner similar to that described heretofore for tube 3, as indicated by lines A', B', C', C'', and D' of Fig. 2.

The part of the system which produces the potentials C and E will now be described. When the transformer 1 is energized, the primary of the transformer 14 is also energized, thereby inducing a voltage in the secondary winding 14b so that alternating voltages which are displaced 180 degrees from each other are impressed upon the grids 19c and 20c, respectively. During the half cycle when the grid 19c is negative with respect to its cathode 19a, the tube 19 is nonconducting and the condenser 26 is gradually charged through the resistor 27, so that the potential of the anode 19b becomes less positive with respect to the cathode 19a. During the same half cycle the negative potential of the grid 20c with respect to the cathode 20a decreases, so that the tube 20 is ultimately rendered conducting thereby substantially short circuiting the condenser 25 through a circuit from the anode 20b to the cathode 20a to tap 22b, through the lower part of resistor 22, to the condenser 25 and back to the anode 20b. It will be apparent that as the condenser 25 becomes charged the negative potential between the slider 22a and grid 3c and therefore between the cathode 3b and the grid 3c decreases as indicated by line C (Fig. 2). This negative potential is modified by a positive bias due to the voltage drop between the upper terminal of resistor 22 and the movable contact 22a as indicated by E in Fig. 2. At the end of the half cycle described, the voltages of the grids 19c and 20c become zero and then reverse so that the grid 19c becomes positive, thereby causing the condenser 25 to suddenly discharge as indicated by the line D, while the tube 20 is maintained nonconducting by the negative potential of the grid 20c, so that now the condenser 25 gradually charges in the manner aforescribed for condenser 26. The primary and secondary voltages of the transformer 14 are displaced approximately 90° from the voltage impressed upon the tubes 3 and 4 by the phase-shifting network comprising the resistor 12 and condenser 13. This assures that the voltage of the grids 19c and 20c render the respective tubes conducting at the moments when the voltages of tubes 3 and 4 are substantially zero. It will be seen that the moment at which the line C intersects the curve B depends upon the value of the potential E, which is superimposed upon the potential of the corresponding condensers 25 and 26, respectively, this value E depending upon the setting of the movable contact 22a. With the contact 22a in its lowermost position the component E is a maximum so that the critical grid potential B will be attained during the earliest possible part of the half cycle, and the tubes 3 and 4, respectively, will be conducting a maximum amount of current, while with the movable contact 22a in its uppermost position the biasing component E is zero and by properly selecting the tap 22b, the maximum value of the voltage C is just sufficient to intersect the curve B prior to reversal of the voltage A, so that the tubes 3 and 4, respectively, are nonconducting. By adjusting the position of

the movable contact 22a it is therefore possible to vary the effective current which the armature 2a receives from the transformer 1.

A motor usually requires a maximum torque for starting from standstill, whereas during acceleration the torque required is less than the maximum. Provision is therefore made to limit the rate of rise of the armature current during acceleration or changes in load. For this purpose the series transformer 5 is arranged to impress upon the circuit of the grids 3c and 4c, a supplemental potential which tends to increase the negative bias on the grids 3c and 4c, respectively. As long as the current in the winding 5a remains constant, very little voltage is induced in the secondary winding 5b. If, however, the current in 5a should suddenly change, it induces a corresponding electromotive force in the secondary winding 5b, the polarity varying with the direction of change. In order to prevent a sudden decrease of the current through the primary winding 5a from increasing the grid potential of the tubes 3 and 4, the rectifiers 6 and 9 are provided to block flow of a reverse current to the condenser 8. The potential derived from the secondary winding 5b is subtracted from the potential B so as to delay the moment of intersection of line C with the curve B and thereby delay the moment of ignition of the tubes 3 and 4 during the respective half cycle.

The system disclosed in Fig. 1 also provides compensation for variations in the terminal voltage impressed upon the armature 2a. Thus the resistor 10 has impressed upon it the terminal voltage of the armature 2a. A part of said resistor is connected by means of the movable contact 10a in series with the winding 5b and the voltage drop therein which is a function of the armature voltage is thus impressed upon the grids 3c and 4c, the arrangements being such that for an abnormal armature voltage the additional bias is added to or subtracted from the voltage E so as to advance or retard the moment of ignition for restoration of normal armature voltage.

The total potential impressed upon the grids 3c and 4c with respect to the cathodes 3b and 4b is therefore composed of the following: the voltage drop of the resistor 10 between the cathodes 3b and 4b and the movable contact 10a, the voltage that may be induced in the winding 5b by a sudden increase of the armature current, the voltage drop between the movable contact 22a and the upper terminal of the resistor 22 and the charge of the condenser 25 or 26.

The field current of the motor 2 is controlled in the following manner:

As long as the armature voltage is below a certain value, that is, below that voltage which corresponds to the normal speed of the armature 60 at full field excitation, the contact 37b of relay 37 is closed. As soon as the motor reaches normal speed, the winding 37a is sufficiently energized to open the contacts 37b. The grids 31c and 32c are alternately energized through the transformer winding 33b in such a manner that the tubes 31 and 32 are conducting during the corresponding half cycle during which the respective anodes are positive with respect to their cathodes, so that with the contact 37b closed, the field winding 2b receives maximum energizing current. When the contacts 37b open, the voltage which is impressed upon the grids 31c and 32c is reduced so that conduction of the tubes 31 and 32 is delayed after the passage of the voltage through

zero for a time depending upon the phase displacement of the grid voltage with respect to the cathode voltage which depends upon the adjustment of the movable contact 36^b. Hence, after the contacts 37^b have opened, the speed of the motor may be varied by varying the adjustment of the movable contact 36^b. It will be recognized that the voltage which is impressed upon the grids referred to is the resultant of the inductive voltage of the condenser 35 and the non-inductive voltage drop through the resistor 36. As the effective value of the resistor 36 is varied by adjustment of contact 36^b, the non-inductive component likewise varies, thus varying the phase displacement of the grid voltage with respect to the voltage of the tubes 31 and 32 in the usual manner.

Fig. 3 shows a modification of the system shown in Fig. 1, wherein an adjustable resistor 40 is interposed in the plate circuit of the tube 20 and a similar resistor 41 is interposed in the plate circuit of the tube 19. Thus the resistors 40 and 41 increase the impedance of the discharge circuit of the condensers 25 and 26, respectively, when the latter are discharged, upon the respective tubes 20 and 19 becoming conducting, as has been described heretofore. It is obvious that instead of putting the resistors 40 and 41 into the plate circuit of the respective tubes they may also be put into the cathode circuits, that is, between the respective cathode and the tap 22^b.

Fig. 4 shows the operation of the system as modified in accordance with Fig. 3. It will be noted that the condensers 25 and 26 are charged at a rate which is determined by the resistors 28 and 37, respectively, in the same manner as has been described heretofore. Therefore the condenser voltage during that half cycle when the voltage represented by the curve A in Fig. 4 is impressed upon the tube 4, rises in accordance with the line F, that is, it rises from a minimum to a maximum value during said half cycle. At the moment when the voltage A passes through zero, the tube 20 becomes conducting, thereby discharging the condenser 25 through a circuit from one terminal of the condenser, through the lower part of the potentiometer 22, over tap 22^b, through the tube 20, through the resistor 40, to the other terminal of condenser 25. This causes the condenser 25 to discharge at a rate which is determined by the impedance of the tube 20 and the resistance of the resistor 40. The voltage of condenser 25 thus varies in accordance with the curve G, which is not necessarily a straight line. The resistor 40 is adjusted so that the condenser attains its minimum charge at the moment when the voltage impressed upon the tube 4 again passes through zero in the opposite direction to repeat another half cycle similar to the one just described. The voltage E is superimposed upon the voltages F and G in the same manner as has been described in connection with Figs. 1 and 2. The operation of the tube 19 and the condenser 26 is similar to that described in connection with tube 20 and condenser 25, as will be apparent from the foregoing description and the diagram Fig. 4. The operation during the next half cycle represented by the curve A' will be apparent from the foregoing description in explanation of Fig. 2, as will also be the effect of changing the biasing voltage E, resulting in the resultant grid voltages F'G' and F''G''.

While the invention has been illustrated and described in connection with a single phase al-

ternating current supply system, it will be obvious that it is also applicable to a system supplied with energy from a polyphase source by interposing a suitable plurality of gaseous discharge tubes between the current supply source and the translating device and controlling each of said tubes in the manner described in the present application.

It will further be apparent that in the modification shown in Fig. 3, the gaseous discharge tubes 19 and 20 may be replaced by high vacuum tubes. Other modifications within the scope of this invention will be apparent to those skilled in the art.

15 I claim:

1. In combination, an alternating current supply source, a translating device, a first gaseous discharge tube having a cathode, an anode and a control electrode and connected for conducting current from said source to said translating device during positive half cycles of the alternating current voltage impressed upon said first tube by said source, a condenser, a resistor and a charging source providing a circuit for charging said condenser at a substantially constant rate, a second gaseous discharge tube having a cathode, an anode and a control electrode and connected to said charging circuit to be normally rendered nonconducting and to discharge said condenser upon being rendered conducting, a connection between the control electrode of said second tube and said alternating current source to initiate conduction of said second tube during alternate half cycles of the voltage impressed upon said first tube by said alternating current source, a connection between said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

2. In combination, an alternating current supply source, a translating device, a first gaseous discharge tube having a cathode, an anode and a control electrode and connected for conducting current from said source to said translating device during positive half cycles of the alternating current voltage impressed upon said first tube by said source, a condenser, a resistor and a charging source providing a circuit for charging said condenser at a substantially constant rate, a second gaseous discharge tube having a cathode, an anode and a control electrode and connected to said charging circuit to be normally rendered nonconducting, and to discharge said condenser substantially instantaneously upon being rendered conducting, a connection between the control electrode of said second tube and said alternating current source to initiate conduction of said second tube during alternate half cycles of the voltage impressed upon said first tube by said alternating current source, a connection between said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

3. In combination, an alternating current sup-

ply source, a motor, a first gaseous discharge tube having a cathode, an anode and a control electrode and connected for conducting current from said source to said motor during positive half cycles of the alternating current voltage impressed upon said first tube by said source, a condenser, a resistor and a charging source providing a circuit for charging said condenser at a substantially constant rate, a second resistor, a second gaseous discharge tube having a cathode, an anode and a control electrode, said second resistor and said second tube being connected to said charging circuit to normally render said second tube nonconducting and to discharge said condenser at a substantially constant rate when said second tube is rendered conducting, a connection between the control electrode of said second tube and said alternating current source to initiate conduction of said second tube during alternate half cycles of the voltage impressed upon said first tube by said alternating current source, a connection between said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

4. In combination, an alternating current supply source, a motor, a first gaseous discharge tube having a cathode, an anode and a control electrode and connected for conducting current from said source to said motor during positive half cycles of the alternating current voltage impressed upon said first tube by said source, a condenser, a resistor and a charging source providing a circuit for charging said condenser at a substantially constant rate, a second gaseous discharge tube having a cathode, an anode and a control electrode and connected to said charging circuit to be normally rendered nonconducting and to discharge said condenser upon being rendered conducting, a connection between the control electrode of said second tube and said alternating current source to initiate conduction of said second tube during the negative half cycles of the voltage impressed upon said first tube by said alternating current source, a connection between said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

5. In combination, an alternating current supply source, a motor, a first gaseous discharge tube having a cathode, an anode and a control electrode and connected for conducting current from said source to said motor during positive half cycles of the alternating current voltage impressed upon said first tube by said source, a condenser, a resistor, and a charging source providing a circuit for charging said condenser at a substantially constant rate, a second gaseous discharge tube having a cathode, an anode, and a control electrode and connected to said charging circuit to be normally rendered non-conducting, and to discharge said condenser upon being rendered conducting, a connection between the control electrode of said second tube and said alternating current source to initiate conduction of

said second tube at the moment when the voltage impressed upon said first tube by said alternating current source passes through zero from a positive to a negative value, a connection between 5 said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

6. In combination, an alternating current supply source, a motor, a first gaseous discharge tube having a cathode, an anode and a control electrode and connected for conducting current from 15 said source to said motor during positive half cycles of the alternating current voltage impressed upon said first tube by said source, a condenser, a resistor and a charging source providing a circuit for charging said condenser at a substantially constant rate, a second resistor, a second gaseous discharge tube having a cathode, an anode and a control electrode, said second resistor and said second tube being connected to 20 said charging circuit to normally render said tube nonconducting and to discharge said condenser at a substantially constant rate when said second tube is rendered conducting, a connection between the control electrode of said second tube and said alternating current source to initiate conduction of said second tube during the negative half cycle of the alternating voltage impressed upon said first tube, a connection between 25 said condenser and the control electrode of said first tube to impress the voltage of the condenser thereupon, and means to superimpose an adjustable unidirectional potential upon the potential impressed by said condenser upon the control electrode of said first tube for varying the moment when said first tube becomes conducting during said positive half cycles.

7. In combination, an alternating current supply source, a translating device, a first pair of 45 gaseous discharge tubes each having a cathode, an anode, and a control electrode and connected for alternately conducting current from said source to said translating device, a condenser and a resistor for each of said first pair of tubes, 50 a charging source providing with each resistor a circuit for charging the respective condenser at a substantially constant rate, a second pair of gaseous discharge tubes one for each of said first pair of tubes and each having a cathode, an anode and a control electrode and each connected to the corresponding charging circuit to be normally rendered nonconducting and to discharge the respective condenser upon being rendered conducting, a connection between the control 55 electrode of each of said second tubes and said alternating current source to initiate conduction of the respective second tube during alternate half cycles of the voltage impressed by said supply source upon the respective first tube, a connection between each condenser and the control electrode of the corresponding first tube to impress the voltage of the condenser thereupon, and means to supply an adjustable unidirectional voltage and to superimpose it upon said condenser 60 voltages to modify the effect of the latter upon said first tubes and to vary the magnitude of said unidirectional voltage which at given moments of the positive half cycles of the voltage impressed upon the tubes by said source initiates current conduction by said tubes.

8. In combination, an alternating current supply source, a translating device, a first pair of gaseous discharge tubes each having a cathode, an anode, and a control electrode and connected for alternately conducting current from said source to said translating device, a condenser and a resistor for each of said first pair of tubes, a charging source providing with each resistor a circuit for charging the respective condenser at a substantially constant rate and a second resistor and a second pair of gaseous discharge tubes one for each of said first pair of tubes and each of said second tubes having a cathode, an anode and a control electrode, each of said second resistors and said second tubes being connected to the corresponding charging circuit to normally render said second tubes nonconducting and to discharge the respective condenser at a substantially constant rate upon the tubes being ren-

dered conducting, a connection between the control electrode of each of said second tubes and said alternating current source to initiate conduction of the respective second tube during alternate half cycles of the voltage impressed by said supply source upon the respective first tube, a connection between each condenser and the control electrode of the corresponding first tube to impress the voltage of the condenser thereupon, and means to supply an adjustable unidirectional voltage and to superimpose it upon said condenser voltage to modify the effect of the latter upon said first tubes and to vary the magnitude of said unidirectional voltage which at given moments of the positive half cycles of the voltage impressed upon the tubes by said source initiates current conduction by said tubes.

JAMES B. REEVES.
